Des. 94,895

COMBINATION CLOCK AND RADIO CONTROL UNIT

Filed March 31, 1934

Mechell Harris

Inventor.

UNITED STATES PATENT OFFICE

94,895

DESIGN FOR A COMBINATION CLOCK AND RADIO CONTROL UNIT

Mechell Harris, Kansas City, Mo.

Application March 31, 1934, Serial No. 51,272

Term of patent 7 years

To all whom it may concern:

Be it known that I, Mechell Harris, a citizen of the United States, residing at Kansas City, in the county of Jackson and State of Missouri, have invented a new, original, and ornamental Design for a Combination Clock and Radio Control Unit, of which the following is a specification, reference being had to the accompanying drawing, forming a part thereof.

The single figure in the drawing shows a front perspective view of the combined clock and radio control unit of my new design.

I claim:

The ornamental design for a combination clock and radio control unit, as shown.

In testimony whereof, I affix my signature.

MECHELL HARRIS.
